UNITED STATES PATENT OFFICE.

GEORGE DORN, OF NEWPORT NEWS, VIRGINIA.

DRAWER AND WARDROBE LOCK.

Application filed March 27, 1923. Serial No. 628,093.

To all whom it may concern:

Be it known that I, GEORGE DORN, a citizen of the United States, residing at Newport News, in the county of Warwick and 5 State of Virginia, have invented a certain new and useful Improvement in Drawer and Wardrobe Locks, of which the following is a specification.

My invention is a new and improved 10 drawer and wardrobe lock and the invention primarily has for its object to provide a lock for the purpose stated, of a simple and effective construction which can be easily and cheaply manufactured, will readily 15 serve its intended purpose and of such construction that it may be quickly placed in position on the drawer or door without the use of fastening screws and without the necessity of chiseling and cutting the part 20 to which the lock is fitted.

In its more specific nature the invention 25 comprises a cylindrical or barrel type of lock which can be fitted into a bored recess or hole and which is provided with a cylindrical plunger that will operate in a cylindrical bore or hole, thus making it possible 30 to apply the lock by simply boring two holes in the drawer or door as the case may be.

In its still more detailed nature the invention 35 comprises a lock of the type stated consisting of a base shell and partition plate between which the plunger operates, the base shell being received in and secured to an outer casing or shell between the front 40 wall of which and the opposite wall of the partition plate the sliding lock plates or tumblers are located.

Another object of my invention is to provide 45 means whereby the lock may be used either as a right hand or left hand lock or as a drawer lock by simply shifting the plunger and the locking plates a one quarter revolution.

Referring now to the accompanying drawings, in which—

Figure 1 is a detail front elevation showing the invention applied to a drawer.

Figure 2 is a vertical section of the drawer 50 showing the lock in elevation.

Figures 3 and 4 are elevations of the lock used as left and right hand locks respectively.

Figure 5 is a detail perspective view of 55 the base shell with the plunger in place.

Figure 6 is a horizontal section on the line 6-6 of Figure 12, the key being in place.

Figure 7 is a detail perspective view of the lock and the key for operating the same. 60

Figure 8 is a detail perspective view of the plunger looking at it from the front.

Figure 9 is a detail perspective view of a portion of the plunger looking at it from the rear. 65

Figure 10 is a vertical central longitudinal section of the lock, the key being in place and the plunger elevated.

Figure 11 is a view similar to Figure 10, the plunger being locked and in this view 70 shown in elevation.

Figure 12 is a view similar to Figure 11, the plunger being in the intermediate position and the keeper being detached.

Figure 13 is a section showing the position of the parts when the lock has been turned to project the plunger to the locking position. 75

Figure 14 is a similar view in the unlocked position. 80

Figure 15 is a similar view with the plunger in the mid position and the keeper removed (Figures 13, 14 and 15 being respectively views corresponding in position to the positions shown in Figures 10, 11 85 and 12).

Figures 16 to 19 inclusive are elevations of the several locking plates.

Figure 20 is an elevation of the partition plate. 90

In the drawings in which like numerals of reference indicate like parts in all the figures, 1 designates the drawer or door, as the case may be, to which the lock is to be fitted. In fitting the lock two holes are 95 bored, one hole 2 to receive the body of the lock and the other, 3 for the plunger to work in, the hole 3 being drilled to intersect the hole 2 through its axis and being drilled deep enough to leave a recess for the bottom end of the plunger when the plunger is retracted, i. e. the lock unlocked. 100

4 designates the base shell which includes a back and a flange 5, the latter having four slots 6 arranged ninety degrees apart and 105 being also provided with threaded holes 7 adjacent the several slots to allow for adjusting the lock to serve as a right or left hand lock, or as a drawer lock in a manner hereinafter more clearly explained. 110

The base shell also includes a boss 8 which forms a guide or bearing surfaces for the back wall 10 of the plunger 9.

The plunger consists of a body having back and front walls 10 and 11 respectively parallel to each other and having cylindrical ends, each tapped to receive the shank 16 of the plunger head 15. The plunger is also provided with a slotted boss 12, into the slot 13 of which the step 42 of the key 37 is adapted to enter to move the plunger up and down. The plunger is also provided with a lock finger 14 that projects through the several locking slots 27 of the locking plates 21 to 24 inclusive. The locking plates have central openings, the key engaging portions 26 of which are definitely cut to cooperate with the several steps 38 to 41 inclusive of the key 37 whereby when the proper key is applied 20 the several locking plates will be moved in unison to locate the locking finger 14 out of the locking recesses 28 of the slots 27 and thereby permit the key to turn to raise or lower the plunger as desired.

17 is the partition plate which divides the lock into two chambers. The plate 17 is adapted to fit within the outer casing or shell 30 and lie against the front edge of the base shell flange, see Figures 6 and 10 to 12 inclusive. The partition plate 17 has a boss 18 to engage with the front surface 11 of the plunger and it is also slotted at 20 to permit the plunger to move up and down. The plate 17 also carries a set of guide fingers 19 to operate in the several slots 25 of the locking plate 21 and to hold the locking plates in proper cooperative relation to one another and the plate 17, the slot 20 serving to hold the plate 17 in proper cooperative relation 35 to the plunger 9 since the slotted end of the boss 12 of the plunger projects into the slot 20 of the plate.

Each plate 21 to 24 inclusive has corresponding guide slots 25 and carries leaf 45 springs 29 which serve normally to hold the plate over to one side of the casing and maintain the several slots 27 in register and continuously tend to hold the finger 14 in the locking recesses 28.

50 The outer casing or shell 30 has holes 34 corresponding in location to the slots 6, and holes 35 corresponding in location to the holes 7, the holes 35 allowing the use of the screws 36 to secure the base shell 4 and outer casing 30 together. The face 31 of the outer casing or shell is recessed so as to provide a curved rim 32 for ornamental purposes and the face 31 is provided with a keyhole slot 33 as indicated.

60 The partition plate 17 may be provided with a stud 43 when a hollow shank key 37 is to be used to guide and hold the key to turn on a definite axis.

If the lock is to be used as a drawer lock 65 the head 15 is screwed into the plunger

while the plunger is located as shown in the several figures of the drawings (excepting Figures 3 and 4). If the lock is to be used as a wardrobe lock, right or left hand lock, the screws 36 are withdrawn from engagement with the base shell holes 7 and the shell 30 is given a one-quarter turn right or left with respect to the base shell 4, it being understood that when this is being done the key shall have been inserted and the plunger 9 projected to the position indicated in Figure 12 so as to clear the casing 30. After the casing has been given the one-quarter turn the screws 36 are replaced. If the lock is to be used in a position where the plunger head must work downwardly to effect the locking act instead of upwardly as in Figure 1, the plunger head 15 is unscrewed from the top of the plunger and screwed into the bottom of the plunger. This would be the case were the lock used on the fixed part of a bureau and the plunger head made to engage a recess in the drawer edge.

While two pairs of slots 6 are shown on the base member 4 one pair alone may be used, the two pairs being provided for convenience in assembling the parts.

It should further be understood that in changing the outer casing to locate the key hole slot from the position shown in Figure 1 to either the position shown in Figure 3 or that shown in Figure 4, the base 4, the plunger 9 and the disks shown in Figures 16 to 20 inclusive remain in their respective positions while the shell 30 is being turned, the object of turning the shell 30 being to locate the key hole slot always in the proper up and down position regardless of whether the plunger and its head are movable in a vertical or a horizontal direction.

The key 37 has steps 38 to 41 inclusive equal in number to the number of locking plates employed, this number being variable to suit the idea of the lockmaker or designer. The key also has an additional step 42 to cooperate with the plunger slot 13.

From the foregoing description, taken in connection with the accompanying drawings, it is thought the complete construction, operation and advantages of the invention 115 will be clear to those skilled in the art.

What I claim is:

1. A lock comprising a base shell and an outer shell secured to the base shell, a partition plate, a plunger operating between said partition plate and the base shell, locking plates in the casing between said partition plate and the front of the casing, said casing having a keyhole slot, a key adapted to enter said slot and cooperate with said locking plates, guides for said locking plates, said plunger having provision to be engaged by said key, a locking finger carried by the plunger, said locking plates each having a locking slot through which said finger pro- 130

jects, and springs for holding the locking plates in a normal position.

2. A lock comprising a cylindrical body, a plunger reciprocably mounted in said body, 5 said body having peripheral openings through which said plunger may project, a head removably carried by said plunger and adapted to be removed from the plunger while the lock is in place in the body on 10 which it is mounted, plunger locking elements within the body and a key adapted to be inserted into the body to release said plunger locking means and operate said plunger.

3. In a lock of the character described, a base shell and a casing shell adjustably secured thereto, said base shell having openings diametrically opposite to each other, said casing shell adapted to be turned on 20 said base shell and having openings to register with the base shell openings, said casing shell having a keyhole slot, a plunger and locking elements operating in said casing, said plunger adapted to project through 25 the opening of the casing and a plunger head carried by the plunger.

4. In a lock of the character described, a base shell and a casing shell adjustably secured thereto, said base shell having openings diametrically opposite to each other, said casing shell adapted to be turned on 30 said base shell and having openings to register with the base shell opening, said casing shell having a keyhole slot, a plunger and locking elements operating in said casing, 35 said plunger adapted to project through the opening of the casing and a head carried by the plunger, said keeper being cylindrical and said casing being cylindrical whereby 40 the lock may be fitted into two bored openings.

5. A lock comprising a base shell consisting of a plate with a cylindrical flange projected at right angle thereto, said flange 45 having openings diametrically opposite to one another, a partition plate lying against the end of said flange, lugs carried by said base shell plate and said partition plate to form guides, a plunger reciprocating between said guides to be projected through 50 and retracted from said openings of the base shell, said plunger having a boss with a key

slot and a locking finger projecting from said boss through an opening in said partition plate, a casing shell having a face and a rim, the latter projecting over said base shell, means for securing said shells together, 55 said casing shell having a keyhole slot at its face, locking plates located in said casing shell between its face and said partition plate, said locking plates having provisions to cooperate with said plunger finger to lock the plunger, a key cooperating with said locking plates to release the plunger, and means continuously tending to hold said 60 locking plates in a locking position.

6. A lock comprising a cylindrical body, a plunger reciprocably mounted in said body, said body having diametrically opposite peripheral openings through which said 70 plunger may respectively project, plunger locking elements within the body and a key adapted to be inserted through the opening in the body to release said plunger locking means and operate said plunger.

7. A lock comprising a cylindrical casing having two sets of diametrically opposite peripheral openings, one set being arranged at right angles to the other set, a base member fitted within said casing and having a 80 pair of diametrically opposite plunger guide openings, a plunger operating in said openings, means to secure said casing and base member together with a pair of diametrically opposite casing openings in register 85 with the base member openings to permit said plunger to be projected through said casing openings alternately according as the plunger is in one position or another, plunger locking elements within the casing, said casing having a keyhole slot into which a key 90 may be inserted to operate said plunger locking elements for the release of the same and to operate said plunger, said casing being adapted to be located on said base with 95 either pair of its diametrically opposite openings in register with the plunger openings of the base, thereby to locate the keyhole slot either in alignment with the plunger or at right angles thereto according as said 100 casing is in one position or another on said base for the purpose described.

GEORGE DORN.
